UNITED STATES PATENT OFFICE.

HENRY C. KOLLING AND WILLIAM MCGILL, OF WICHITA, KANSAS.

ADJUSTABLE TRACK.

Application filed May 24, 1922. Serial No. 563,218.

To all whom it may concern:

Be it known that we, HENRY C. KOLLING and WILLIAM MCGILL, citizens of the United States, and residents of Wichita, in the county of Sedgwick and State of Kansas, have invented certain new and useful Improvements in Adjustable Tracks, of which the following is a specification.

This invention relates generally to tracks and more particularly to a track which is adapted to be placed upon a series of steps, such as the steps leading to a dwelling or like structure, to provide a plain surface over which wheeled and rollingly supported articles of furniture and vehicles, such as baby-carriages, can be moved without being subjected to the shocks and jars that would be incident to their movement over a series of steps.

An object of our invention is to provide a track of the character described which includes a pair of rail members, at least one of which is movable relatively to the other to adjust the width or gauge of the track as required for the accommodation of vehicles and articles of furniture of various widths.

Other objects and advantages will be apparent from the following description, and the novel features of the invention will be particularly outlined in the appended claims.

Our invention is illustrated in the accompanying drawings, forming a part of this application, in which

Figure 1 is a side elevation showing a practical embodiment of the invention operatively applied to a series of steps leading to an elevated structure,

Figure 2 is a vertical section through the structure exhibited in Figure 1,

Figure 3 is a fragmentary view similar to Fig. 1, showing the rail members of the track in folded or inactive position, and

Figure 4 is a perspective view showing a hinge member comprised in the device.

In carrying out our invention, we provide a pair of longitudinal rail members 1, 2 which are of equal length and of substantially identical construction, both being of channel-formation and being formed of any suitable material, such as a light gauge

metal, wood or in fact any relatively light material of sufficient strength to sustain the weight of articles which may be moved therealong, as will presently appear. The 55 track member 2 is arranged transversely of the steps of a series of steps indicated generally at 3 so that the web portion of the rail member is disposed against the outer edges of the horizontal members of the respective steps and the upper end of the rail member abuts the outer edge of an elevated horizontal platform 4, which may be the floor of a porch or like structure, and the lower end of the rail member rests upon a 60 horizontal surface 5 at the lower end of the series of steps. The rail member 2 is secured to the steps in the position described in any suitable manner, as by means of 65 nails or screws 6 projected therethrough 65 into the horizontal members of the steps and having their heads counter-sunk or flush with the upper or outer face of the web portion of the rail. It is to be observed at this point that the rail member 2 is positioned adjacent to one side of the series of 70 steps so as to leave the major portion of the series of steps unobstructed and available 75 for use in the usual manner.

The rail member 1 is movably supported 80 in parallel relation to the rail member 2 by means of a pair of spaced guide members 7—7 having offset end portions 8 secured by screws 9 or the like to the vertical members of the upper and lower steps of the series, 85 and a pair of connectors 10 having portions mounted to slide upon the guide members 7 and outstanding portions 11 to which the flange of the rail member 1 proximate to the rail member 2 is swingingly connected. 90 The guide members 7 extend transversely of the rail members 1, 2 and the end portions thereof underlying the fixed rail member 2 need not be offset but can be extended in axial alignment with the intermediate or 95 major portion thereof into engagement with any suitable support, such as a side member 12 of the frame for the series of steps, as indicated by the dotted lines in Figure 1. It is only essential to my invention that the 100 members 7 and the hinge members 10 co-operating therewith be so disposed that the

rail member 1 can be moved bodily toward and away from the rail member 2 in parallel relation to the latter and in the plane of the latter when in active position.

5 As illustrated to advantage in Figure 4, each of the connectors 10 is made of a single piece of wire bent to provide a loop 13 at one end thereof, a second loop 14 immediately of the ends thereof and the outstanding portion 11 which is provided with an eye or a loop portion 15 at its end. The loop portions 13 and 14 are adapted to slidably embrace one of the guide members 7 at spaced apart points and the loop portion 15 is adapted to enter one of the cut away portions 16 in the hollow bead or rolled portion 17 at the outer edge of the flange of the rail member 1 proximate to the rail member 2. A pintle 18 extending through the bead 17 passes through the loop 15 of the connectors 10, whereby the rail member 1 is held against any appreciable axial movement relatively to the guide members 7, 7. The second flange of the rail member 1 and the 20 flanges of the rail member 2 are shown as being provided with beads similar to the bead 17 along the outer edges thereof and the same reference numeral has therefore been used to designate the respective beads 25 of the two rails.

From the foregoing description of the various parts of the device, the operation thereof may be readily understood. The rail member 1 can be slidably moved along 30 the guide member 7 to position it at a desired distance from the rail member 2 so as to accommodate vehicles or articles of furniture of different widths which it is desired to move up or down the series of 35 steps. The rail member 1 is releasably held against movement from adjusted position in the direction away from the rail member 2 by flexible holding members, such as the chains 18, each of which is connected at one 40 end to the rail member 2 and is adapted throughout its length for engagement with one of the hooks 19 or like co-operating element carried by the rail member 1.

When the device is not in use, the chains 45 18 are disconnected from the rail member 1 and the latter is slidably moved along the guide member 7 until adjacent to the rail member 2. The web portion of the rail member 1 is then swung upwardly and 50 downwardly about the axis of the pintle 18 to rest in superimposed position upon the rail member 2, as illustrated in Figure 3. It will be apparent that both rail members 55 will occupy but little space when in inactive position and will not interfere with the use of the series of steps 3 in the usual manner.

Obviously, our invention is susceptible of embodiment in forms other than that illustrated in the accompanying drawings, and 60 we therefore consider as our own all modifi-

cations of the forms of the device disclosed herein, which fairly fall within the scope of the appended claims.

We claim:—

1. A track of the character described comprising a pair of longitudinal rail members, and means adjustably connecting the rails together in parallel relation and permitting of movement of one rail from a position in which it is disposed laterally of the other rail to a position in which it is superimposed upon the latter. 70

2. A track of the character described comprising a pair of longitudinal rail members, means adjustably connecting the rails together in parallel relation and permitting of movement of one rail from a position in which it is disposed laterally of the other rail to a position in which it is superimposed upon the latter, and other means for detachably connecting the rail members together to hold the rail members against movement apart from a predetermined adjusted relation. 80

3. A track of the character described comprising a pair of longitudinal rail members, each being of channel formation, means for fixedly securing one of said rail members to a support, a pair of guide members extending transversely of said fixed rail member adjacent to the ends thereof, and a pair of connectors, each attached at one end to the second rail member and slidably embracing one of said guide members to position the second rail member in parallel relation to the fixed rail member and to permit of bodily movement of the former relatively to the latter. 90

4. A track of the character described comprising a pair of longitudinal rail members, each being of channel formation, means for fixedly securing one of said rail members to a support, a pair of guide members extending transversely of said fixed rail member adjacent to the ends thereof, and a pair of connectors, each pivotally attached at one end to the side of the second rail member proximate to the fixed rail member and slidably embracing one of the guide members, whereby the second rail member is disposed in parallel relation to the fixed rail member and is movable bodily relative to the latter and is also swingable in the arc of a circle from the plane of the fixed rail member to a superimposed position upon the latter. 100

5. A track of the character described comprising a pair of longitudinal rail members, each being of channel formation, means for fixedly securing one of said rail members to a support, a pair of guide members extending transversely of said fixed rail member adjacent to the ends thereof, a pair of connectors, each pivotally attached at one end to the side of the second rail member proximate to the fixed rail member and slid- 110

ably embracing one of the guide members, whereby the second rail member is disposed in parallel relation to the fixed rail member and is movable bodily relative to the latter and is also swingable in the arc of a circle from the plane of the fixed rail member to a superimposed position upon the

latter, and other means for detachably connecting the rail members together in adjusted position to hold the movable rail member against movement away from the fixed rail member.
